UNITED STATES PATENT OFFICE

2,570,418

ENGINE COOLING SYSTEM

Farrile S. Young, Kansas City, Mo., assignor to
 Panhandle Eastern Pipe Line Co., Kansas City,
 Mo., a corporation of Delaware

Application April 21, 1948, Serial No. 22,415

2 Claims. (Cl. 123—41.45)

1

This invention relates to field compressors, and particularly to a cooling system for the engines used in such compressors, and combines an arrangement such as shown in my Patent No. 2,424,010 issued July 15, 1947, for cooling the oil with an exhaust induced air flow for cooling the water whereby the combined cooling effect of the cooled oil and water maintain the compressor and engine at operating temperatures so they can operate for long periods without attention.

The principal objects of the present invention are to provide a portable type compressor having an arrangement for cooling oil and jacket water without use of any power; to provide devices applicable to both liquid and vapor stage cooling of the internal combustion engine used with the compressor; to provide a heat exchanger for cooling the oil from the engine of the compressor; to provide means for supplying gas from a source of supply to said heat exchanger for cooling the oil from the engine; to provide an air-fin type jacket water cooler for effecting the cooling of the jacket water; to provide means for exhausting gases from the motor from the engine to a venturi above the fin-type water cooler, and effect heat transfer from the water to the air; and to provide a device which is simple, economical to manufacture and efficient in operation for the purpose set forth.

In accomplishing these and other objects of invention, I have provided approved details of structure in the preferred form of which is illustrated in the accompanying drawing, wherein:

Fig. 1 is a perspective view illustrating my invention showing a part of the housing broken away to illustrate the air-fin type water cooler.

Fig. 2 is a longitudinal sectional view through the heat exchanger forming part of my invention.

Fig. 3 is a vertical cross-sectional view through the canopy and venturi above the housing, particularly illustrating the air-fin type jacket water cooler and the exhaust from the engine to the venturi.

Referring more in detail to the drawings:

1 designates a field compressor embodying the features of my invention supported on skids or the like (not shown) for movement from place to place, if desired. 2 designates a housing for the compressor, having a sloping roof as indicated at 3.

4 designates an engine of ordinary construction having a plurality of cylinders 5, an exhaust manifold 6, free air header 7 and a crank

case 8, adapted to contain lubricating oil for the motor. The compressor has a plurality of chambers 9 each having connection with a heat exchanger 10 and a discharge header 11, said discharge header carrying the compressed gas to the discharge side of a pipe line 12. Leading from the inlet side of the line 12 is a pipe line 13 which connects to the heat exchanger as indicated at 14, Fig. 1, the line 13 supplying a source of gas to the heat exchanger. The heat exchanger is connected to the chambers 9 by pipes 15.

The heat exchanger preferably consists of a cylindrical shell 17 provided at the respective ends with heads 18, having a plurality of openings and receiving a plurality of tubes 19 around which gas entering from pipe 13 will pass through the heat exchanger, to pipe lines 15 to the compressor chambers 9. The tubes 19 may be attached to the heads 18 by swaging or other suitable means. A closed header 20 is attached to one end of the heat exchanger and a header 21 is attached to the opposite end having a partition 22 forming compartments 23 and 24. Leading from the compartment 23 of the heat exchanger is a line 25 having its opposite end connected to the crank case 4 as indicated at 26. A line 27 leads from the compartment 24 of the header 21 of the heat exchanger and has its opposite end connected to a pump 28 which also connects to the crank case 4 as indicated at 29.

I also preferably provide a fuel gas line 30 leading from the gas line 12 to the motor 4 as indicated at 31 for supplying fuel thereto.

Suitably supported on and spaced above the roof 3 as by posts 32 is a canopy 33 comprising a frame 34 and upwardly and inwardly sloping walls or top 35 terminating in a circular housing 36. The housing 36 has a tapered top 37 having an opening 38 for a stack 39. The stack 39 is provided with a restricted portion forming a venturi 40.

Located within the framework 34 and extending longitudinally thereof are a plurality of tubes 41 forming a radiator for water for the engine. The radiator is here illustrated as consisting of two rows of tubes, one above the other, through which the water from the engine flows for cooling of such water before returning to the engine.

A line 42 is connected with said tubes and has its opposite end connected to a chamber 43 of the engine 4 as indicated at 44. A line 45 is attached to the upper side of said tubes and leads to the engine 4 for return of water to the engine after it has been cooled. A pump 46 is connected to the

water chamber of the engine for circulation of the water.

A line 47 is connected to the exhaust manifold 6 of the engine and has its upper end extending through an opening 48 in the housing 36 and its end turned upwardly forming a nozzle aligning with the venturi in the stack 39 as indicated at 49.

Operation of a device constructed and assembled as described is as follows:

Gas is supplied from line 12 from a source of supply (not shown) and line 30 leads from such line to the engine for supply of fuel gas for operation of the engine. Gas also from the source of supply from line 12 enters the heat exchanger through line 13 usually at a comparatively low temperature and passes around the tubes 19 in the heat exchange. Oil is pumped from crank case by pump 29 through line 27 to the heat exchanger and passes through tubes 19 cooled by the gas and is forced back through the line 25 leading back to the crank case, the oil being cooled as it passes through the cooled tubes in the heat exchanger. After the gas passes through the heat exchanger, it is returned to line 12 through line 11 leading from the chambers 9 of the compressor.

The canopy 33 is spaced a sufficient distance from the roof 3 so that air will pass upwardly around the tubes 41 in the canopy and thence upwardly through the tapered top 35 to housing 36. The exhaust gas jet from the engine passes through tube 47 to the housing and the nozzle thereof being in alignment with the venturi 40 of the stack will cause an increased situation of air through said venturi and thus effect a flow of air upwardly around the tubes 41 to cool said tubes with air from atmosphere, thus cooling the water from the engine. After the water has passed through the tubes and is cooled it is returned to the engine through line 45.

While I have here shown the water-cooling system located above the compressor it will be obvious it may be located to the side or at any convenient place adjacent the compressor.

It will be obvious from the foregoing that I have provided an improved cooling system structure for a field compressor and cooling of the oil and water for the engine without extraneous sources.

What I claim and desire to secure by Letters Patent is:

1. In combination with a compressor having an engine operated by gas from a gas supply line, said engine having a crank case for containing oil

and means in said gas line for cooling said oil, a water cooling system comprising a canopy located above the compressor, said canopy having an inwardly tapered top terminating in a housing above the canopy and having communication with the interior thereof, a stack having a venturi leading from the housing, a radiator in said canopy, and a pipe leading from the exhaust of the engine to said housing, said pipe having its discharge end aligning with said venturi for discharging the exhaust therethrough and inducting a current of air through the radiator to cool the water therein, and means for circulating water from the engine through said radiator whereby the combined cooling effected by the cooled oil and water maintain the compressor and engine at operating temperature.

2. In combination with a compressor contained within a housing structure having an engine operated by gas from a gas supply line, said engine having a crank case for containing oil and means in said gas line for cooling said oil, a water cooling system comprising a canopy located above and spaced from the compressor housing structure, said canopy having an open bottom and an inwardly tapered top terminating in a housing above the canopy, a stack having a venturi leading from the housing, a radiator supported at and extending across the open bottom of said canopy, and a pipe leading from the exhaust of the engine to said housing, said pipe having its discharge end aligning with said venturi for discharging the exhaust therethrough and inducing a current of air through the radiator, and means for circulating water from the engine through said radiator whereby the combined cooling effected by the cooled oil and water maintain the compressor and engine at operating temperature.

FARRILE S. YOUNG.
